UNITED STATES PATENT OFFICE.

JOHN TWARDUS, OF HARTFORD, CONNECTICUT.

DIRIGIBLE BALLOON.

Application filed June 10, 1920. Serial No. 387,943.

To all whom it may concern:

Be it known that I, JOHN TWARDUS, a subject of the Government of Poland, and a resident of Hartford, in the county of Hartford and State of Connecticut, have invented new and Improved Dirigible Balloons, of which the following is a specification.

My invention relates to the class of devices above named and an object of my invention, among others, is to provide a balloon with means for utilizing the lifting medium to the fullest extent; to provide means for floating the balloon in the air with the use of a minimum amount of said lifting medium; to provide means auxiliary to said lifting medium for determining the elevation of said balloon; to provide means that will permit easy and safe landing of the balloon under deflated conditions of the bag; to provide for extreme rigidity in the structure as a whole; and further to provide a structure having other and various uses as will appear from the following description.

A structure embodying my invention and in the construction and use of which the objects herein set out, as well as others, may be attained, is illustrated in the accompanying drawings, in which—

Figure 1 is a view in side elevation of a balloon or airship embodying my invention.

Figure 2 is a bottom view of the same.

Figure 3 (Sheet II) is a view in front elevation, parts beyond being omitted.

Figure 4 is a detail top view of a portion of the passenger car and of one rigid wing or plane illustrating the manner of attaching an elevating plane thereto, and the seats for the passengers, together with the ladder to provide entrance to said car and the ladder leading therefrom to the pontoons.

Figure 5 is a view in side elevation of that part of the structure shown in Figure 4.

Figure 6 shows a detail top view illustrating the construction and operation of the cylinders for contracting the gas bag.

Figure 6^a is a detail end view of said cylinders.

Figure 6^b is a view in cross section through the frame supporting said cylinders.

Figure 7 shows a detail top view of the drums for stretching the bag.

Figure 7^a is a detail view illustrating the method of attaching the stretching cord to said drum.

Figure 7^b is a detail end view of said drums.

Figure 8 shows a detail side view, scale enlarged, of the connectors for contracting the gas bag.

Figure 8^a is a detail end sectional view of 60 said connectors.

Figure 9 is a detail view, scale enlarged, illustrating the manner of joining the connectors.

Figure 9^a is a detail view illustrating the 65 construction of the stuffing boxes through which the contractors pass from within the gas bag.

Figure 9^b illustrates the thin plates comprising a portion of the stuffing box struc- 70 ture.

Figure 10 is a detail view, scale enlarged, illustrating the wrapping about the contractors within said stuffing boxes.

Figure 11 is a side view of the steering 75 mechanism and the elevating plane operating mechanism.

Figure 11^a is a front view of said mechanism.

Figure 11^b is a top view of said mechanism. 80

Figure 11^c is a detail view showing the construction of a part of such mechanism.

Figure 11^d is another detail showing the 85 construction of such mechanism.

Figure 12 is a detail view illustrating the manner of suspending the hull from the gas bag and for holding the bottom of said bag in a raised position.

Figure 13 is a detail view, scale enlarged, 90 illustrating the arrangement of the primary and yielding tension supports.

Figure 13^a is a detail view, scale enlarged, further illustrating the arrangement of the primary and yielding tension supports. 95

Figure 13^b is another detail view, scale enlarged, illustrating said supports.

Figure 14 is a side view, on enlarged scale, illustrating the positioning struts and their connection with the wire suspension braces 100 and with the primary and yielding tension supports.

Figure 14^a is a top view of the parts shown in Figure 14.

Figure 15 is a detail top view, scale en- 105 larged, illustrating the yielding lifting mechanism for the elevating bi-planes.

Figure 15^a is a detail side view of said lifting mechanism.

Figure 16 is an end view of that part of 110 the structure illustrated in Figures 4 and 5.

Figure 17 is a side view, scale enlarged,

- illustrating the traction wheels and their manner of attachment to the pontoons.
- Figure 17^a is an end view of the same.
- Figure 18 is a view, still further enlarged, illustrating the construction of said traction wheels.
- Figure 19 is a view, still further enlarged, illustrating the construction of said wheels.
- Figure 20 (Sheet I) is a diagrammatic view illustrating the arrangement and disposition of the several cords for operating different mechanism in the structure, this view illustrating the pontoons and planes at the after-part of the structure.
- Figure 21 is a detail view illustrating the manner of mounting the rudders.
- Figure 22 is a detail face view, scale enlarged, illustrating the manner of connecting the fins to the sides of the balloon structure.
- Figure 22^a is a sectional view further illustrating said parts.
- Figure 23 is a sectional view illustrating the construction of the pontoons located at the ends of the lowermost planes or wings.
- Figure 23^a is another sectional view, scale reduced from the scale of Figure 23, illustrating said parts.
- Figure 23^b is a side view illustrating said parts.
- While one purpose of the invention is to provide a structure that shall be only partially supported by gas within the bag, yet there are various features of invention embodied in the structure herein illustrated and described that are applicable to and may be embodied in flying apparatus of various types.
- In the accompanying drawings the numeral 5 indicates a gas bag, that is streamline shape, and that is composed of three sections disposed lengthwise of the bag, the forward section 6 being pointed and terminating in a nose at its front and being round in cross section, the mid-section 7 being cylindrical in shape and the rear section 8 being ellipsoidal in shape with its axis bent down so that the bottom of the bag extends in a straight line from the rear part of the forward section to the rear end of the bag. A contraction web 9, comprising a narrow strip of canvas is attached to or depends from the top of the inside of the bag and extends throughout its length, said web being engrailed at portions of its lower edge, the indented parts having pockets 10 within which secondary distributors, comprising short cords 11 disposed in small curves are secured, the ends of adjacent distributors 11 being twisted together to form connectors 12 (see Figure 8) between the secondary distributors and main distributors 13, each of the latter of which comprises a cord disposed in the form of an arch extending substantially the whole length of

one of the sections of the bag, as shown in dotted outline in Figure 1 of the drawings, the connectors being secured to the main distributors in any suitable manner, as by tying, all of these distributors being 70 for the purpose of distributing a pulling force applied at the angles of the main distributors, in a manner to be hereinafter described. The upper part of each of the arches comprising the main distributors 75 meets the lower edge of the contraction web, that at these points, is formed into pockets of considerable length and each of a shape corresponding to the shape of the arch that is to be secured in said pocket. Each main 80 distributor meets at each of its ends an adjoining distributor and one of the longer connectors, these parts comprising three ends that are secured together in any suitable manner, and as shown in Figure 9, preferably 85 to form a loop to receive a contractor that is secured therein. There are four of these contractors, a forward contractor 14, a rear contractor 15, and two central contractors 16 and 17, each of which extends 90 through the bottom of the gas-bag to an accessible position where they may be operated by devices to be hereinafter described. Each of the openings through the gas-bag 95 is made airtight by a stuffing box 18, (see Figure 9) preferably of metal, and secured at its lower end, as by soldering, to a clamp plate 19 having rounded edges and attached as by means of screw bolts and nuts to a cooperating clamp plate 20, said bolts being 100 secured to the plate 19, as by means of solder, to render the parts gas tight. The gas bag 5 is securely clamped all around the edge of each of the openings between said clamp plates, the lower one of which is formed 105 with a recessed hub 21 for attachment to a transverse member of the hull of the balloon and in a manner to be hereinafter described. The edges of said openings through the bottom of the bag are formed with pockets 110 to receive solid rubber rings 22. The packings within the stuffing boxes each comprises a strip of leather 23 disposed spirally around the cord constituting a connector, said leather being enveloped in rubber packing 24 under tension, said packing resting 115 against a thin plate in the bottom of the stuffing box, and a like plate 51 placed on top of said packing, and the whole being compressed tightly within the stuffing box 120 by means of a gland projecting from the inside of a screw cap 25, in a manner that will be readily understood. Said thin plates are each formed in halves to facilitate their operation and the cord, especially as to that 125 part passing through the stuffing box, should be smooth to enable its movement within said box and also to render the latter gas-tight.

Fins 26 project laterally from opposite 130

sides of the bag at about the vertical center and extending lengthwise thereof along its central section and onto a portion of each of its end sections. These fins are formed of 5 wide strips of canvas, their outer edges being shaped on indented curved lines and bound as by means of a cord sewed into a pocket along each edge. The extreme points 27 of these fins are secured to vertically positioned frames, in the structure shown herein there being four of these points and frames, the latter resting upon rigid planes and being held and operated as by means of 10 stays 28 to be hereinafter described.

15 The hull 29 is suspended from the bottom of the gas bag and extends for substantially its whole length along the center thereof. It is a frame construction, (see Figure 16) substantially rectangular in form in cross section 20 and comprises longérons 30 at each of the four corners with cross pieces 31 and uprights 32 arranged in sets and disposed more or less regularly at intervals along the longérons and secured thereto in any suitable 25 manner. The parts of the frame at the forward and rearward ends of the hull may be wire braced diagonally or otherwise strengthened in any suitable manner, common to structures of this class. The central 30 portion of the hull, constituting the passenger car, will be built stronger than the ends by the employment of braces and struts in a manner to provide a passageway along the car, as herein shown in Figure 16 upper and 35 lower braces 33 and 34 being secured to the cross pieces and uprights of each of the rectangular frames, the lower ends of the latter being set back from the crosswise center of the frame a distance sufficient to provide a 40 passage. Two upright struts 35 defining the sides of the passageway extend from the bottom of the braces 34, in each of said frames upwardly to a point where they are secured to the braces 33 and diagonally arranged struts 36 extend from the braces 33 45 at their points of connection with the upright struts into the angles between the cross pieces and uprights at the upper corners of the frame.

50 The means for suspending the hull from the gas bag and for securely positioning it with respect to said bag comprises positioning struts 37 (see Figures 3 and 12) pivotally secured to the upper longérons at each 55 of the joints of the cross pieces and uprights 31-32, and extending in opposite directions laterally from the hull for its entire length. The outer ends of these struts are connected with the bottom longérons at the joints of 60 the lower cross pieces and uprights by wire suspension braces 38, and the manner of arranging these connections and of attaching them to the gas bag forms an important feature of my invention, this being as follows:

65 Underneath the bag, and extending there-

around, on a line passing through the points where the tangents of the transverse circles formed by the inflated bag incline at angles of about forty-five degrees to the perpendicular, are arranged primary supports 39 for 70 yielding tension supports 40. (See Figure 13). Said primary supports comprise bends at the intersection of small upwardly extending curves into which a cord 41 extending around the bag on its under surface is 75 formed, and as clearly shown in Figure 1 of the drawings, this arrangement concentrating all vertical lifting forces at said primary supports, thereby distributing the stresses on the gas bag uniformly all around 80 the bottom thereof. The yielding tension supports 40 comprise loops formed in a cord 42 extending in a straight line around the under surface of the bag under and close to the cord forming the curves 41, this cord 42 85 running loosely through a continuous pocket 43 comprising a folded strip securely fastened at its upper edge to the bag by stitching and cementing, said supporting loops 40 projecting outwardly through openings 45 90 formed at regular interval along the pocket 43, said loops resting within and being supported by the bends or supports 39. The loops 40 are secured tightly in slots in the outer ends of the positioning struts 37, and 95 the upper ends of the wire suspension braces 38, hereinbefore referred to, are securely fastened within said loops. Each of the loops 40 is subjected to two opposite pulling forces, one by the primary support in 100 the cord 41 in an upwardly direction and the other by the braces 38 in a downwardly direction, (see Figure 14) this developing stresses in the cord 42 comprising the yielding tension support 40 all around the bag 105 proportional to the lifting power of gas within the bag and independently of gas pressure therein.

I make use of the naturally low pressure of the gas in the lower part of the bag by 110 elevating this lower part and holding it in this raised position by the stiffening or positioning struts 37 and above the natural cross sectional curve of the inflated bag (see Figure 12) thus flattening its bottom and 115 thereby reducing its height and consequently permitting the propelling power of the screws to be located nearer the axis of resistance than would otherwise be the case. Further than this the bottom is developed 120 into a substantially flat surface that is valuable as a resistance to downward movement of the entire structure, and also as a lifting surface to promote elevating action when running.

125 The hull on lines passing through the two sets of rigid elevating planes that support motors, to be hereinafter described, and at points on the hull, where most of the weight is concentrated for support, is extended 130

downwardly in the form of two small cabins 79. Both of said extensions 79 are constructed as integral, inseparable parts of the hull by means of prolonged vertical members 5 extended downwardly across the lower longérons of the hull, as shown in Figures 1, 3, 5 and 16 of the drawing, said structure also including diagonal stiffening members, thereby making a strong, stiff construction 10 of said hull and extensions. Both of said extensions are substantially of equal dimensions and shape, preferably rounded in the front and with the bottom of each elevated toward the front and serving an additional 15 purpose as pilot houses, having unobstructed view all around. These extensions also serve as a basis for the means for supporting the motors, by imparting rigidity to the wings hereinafter described. Said extensions 20 also serve as points of support of the whole elongated structure to keep it above ground and above water in a satisfactory manner as to its lengthwise balance. As shown in Figures 1, 3 and 5 of the drawings 25 the lower parts of said extensions are made watertight in any suitable manner so that they will float on water as a substitute for pontoons.

Traction wheels 80 are mounted, one under 30 each pontoon, and preferably under an imaginary line connecting the gravity centers of the motors, said wheels being each mounted between supporting bars 81 (see Figure 17) extending lengthwise along the center 35 of the bottom of the pontoon. To secure rigidity of these structures to withstand shock upon said wheels when alighting I provide braces 82 secured to and extending from the bars 81 diagonally upward in opposite directions from the sides of each pontoon close to vertical pontoon supports 83 (see Figure 16), said braces being securely fastened to both spars of the lowest rigid plane or wing 54 and substantially under 45 the vertical axis of the motor above them. Ladders 44 for the pilot rest upon the bars 81 and extend to openings in the bottom of the passenger car. The wheels 80 project into the pontoons within which they 50 are covered by hoods 85 made watertight and arranged to provide a lower step at the bottom of a ladder. Each of said supporting wheels is of the suspension type and is made watertight as follows: Each wheel is 55 supported to rotate on an axle 86 in bearings on the bars 81, flanges 87 being rigidly secured to the axle and spaced to receive the wheel between them. Each wheel comprises two spoke plates 88 of ordinary construction 60 with the usual spokes for supporting the rim, and outside of each spoke plate is located a metal ring 89 free to rotate on the axle but held in close contact with the adjacent flange 87 by a solid rubber ring 65 90. A flat rubber ring 91 is formed with

contracting qualities to cause it to hug tightly into a groove in the edge of a ring 89, and a cover 92 is tightly cemented or otherwise secured to the ring 91 and the rubber tire on each side of the wheel. 70

The means for operating the cords or other flexible supports comprises the contractors at the forward and stern part of the balloon, and as they are similar in construction it will be understood that a description of one 75 applies equally to the other. The ends of the several contractors 14, 15, 16 and 17 extend downwardly through holes in the recessed hubs 21, cross pieces 31 and plates on the bottoms of said cross pieces. Bolts 80 with their heads located in the recesses in the hubs 21 secure the stuffing box structures tightly in place, said bolts also securing the plates on the bottoms of the cross pieces, which plates sustain brackets 53 rotatably supporting sheaves 52, said contractors, after passing through the holes above described, extending about the sheaves 52 and along the hub to a location 85 near the center of the passenger car, at which point they are secured to contracting cylinders, there being one cylinder for the contractors from the forward part of the bag and one cylinder for the contractors from the rearward part of the bag. Each 90 of these cylinders has a large section 46 and a small section 47, (see Figure 6) the former to receive the contractors that operate the midsections of the bag, and the latter to receive the contractors that operate the extreme sections of the bag. This causes the cords operating the extreme and smaller sections of the bag to be wound on the cylinders when they are turned more slowly than the winding of the cords operating the mid 95 and larger sections of the bag, with a result that as one cylinder is turned to operate the cords to contract the bag, such contraction will take place evenly along the sections of the bag from the front to the rear of the sections operated by that cylinder and along the whole bag when both 100 cylinders are operated. 110

The above mentioned word "evenly" pertaining to contraction, interpreted precisely 115 means that depression of the gas-bag after such contraction, will be in proportion to the ratio of its diameters, because the larger and smaller sections of both cylinders vary in diameter accordingly. 120

For obvious technical reasons, it can be readily understood that with an increased size of gas-bag the number of varying sections on each cylinder and corresponding contractors, also parabola curved distributors, must be so increased as to meet the increased resisting forces in a proper way thereby avoiding concentration of too big 125 stresses in the material.

The cylinders are all supported by a sin- 130

gle frame 48 attached to and depending from upper cross pieces 31 of the hull frame. These cylinders may be turned in any suitable manner, as herein shown a worm wheel 5 on each cylinder meshing with a worm on a shaft 49 having a handle 50, this construction holding the cylinders from turning movement at any point to which they may have been turned. By operating the cylinders the top of the gas bag may be pulled inwardly, thereby decreasing the volume of the bag and also increasing the pressure therein, and vice-versa. By pulling in one part of the bag more than another, the gas 10 may be shifted to a degree from one end of the bag to another for the purpose of balancing the structure, or for the purpose of inclining it for other reasons.

The pulling forces and strains on the 20 small distributors 11 and on the large distributors 13, as well as such strains upon the primary supports 39 of curved cord 41, are distributed evenly over the entire surface of the bag, that resists such forces, by 25 arranging such distributors and supports in parabola, that is, catenary, curves of greater or lesser degrees, said distributors and supports thus being arranged in a form to secure the greatest advantages in the transmission of such strains and forces.

The passenger car may occupy such portion of the hull as may be desired, in the structure herein shown such car occupies the mid section 7 of the ballon and extends for 30 a short distance on to each of the sections 6 and 8. Extending laterally from each side of this car, at or near its ends and secured to the longérons thereof, I provide rigid wings or planes 54—55 that, next to the 35 car, are in the form of bi-planes and that bear the nacelle struts of motors 56, preferably four in number. Lifting or elevating bi-planes 57 (see Figures 4 and 5) are pivotally attached to the rear spars of said 40 wings, in position to receive the blast from the propellers 58, in the preferred form of construction, the upper and lower members of the elevating planes being secured respectively to the upper and lower spars of said 45 wings, the members of each pair of elevating planes being connected by two plane elevating struts 62 pivotally secured thereto. Outside of the nacelle struts for the motors 50 are arranged inter-plane struts 59 forming part of a support for a third plane 60 on each side of the car, supported above and upon the plane 55, as by struts 61. These struts divide the planes into sections, and the lower plane is, at each end, shorter than 55 the plane above it by about the length of one of said sections. At the four points of pivotal connection of each elevating bi-plane with the rigid plane supporting it, and on top of the spars of said rigid planes, are secured 60 lifting springs 63 (see Figure 15) connected

with the elevating planes in a manner to hold them in raised positions. In the structure as herein shown these springs are enclosed within housings with a lifting rod 64 attached to the free end of each spring and 70 extending therethrough to a post 65 rigidly secured to the spars and ribs of each elevating plane (see Figure 15). Elevating plane actuators comprising cords 66 extend from the points of connection of the struts 62 75 diagonally downward around sheaves 67—68 (see Figure 20) supported on the rear spars of the lowest rigid wing or plane, said cords being joined at a point after passing said sheaves into a single cord that passes 80 over sheaves 69—70 to a pulley 71, this description applying to each pair of elevating planes. The pulleys 71 are mounted on an actuating bar 72 to be hereafter described.

Each member 73 of a pair of rudders is 85 pivotally secured to the hull, one member on each side thereof and at its forward part, and another pair of rudders is secured at the rearward part of the hull in a similar manner. Each of these four rudders is pivotally mounted on a rudder frame 74 preferably of steel tubing bent from a single piece of metal (see Figure 21) attached at its front ends to the upper and lower longérons of the hull, thereby forming, with the 90 vertical wooden members, connecting both longérons, a form of trapezium, wire braced diagonally between its members thereby comprising a very stiff structure in vertical planes, said structure being wire braced on both sides to the longérons to retain it perpendicular to the hull. A rudder is preferably attached to the shorter upright of each of said frames, the outer upright being enclosed in the body of said rudder on one side 95 on the median vertical line thereof. The centers of the two horizontal wooden rudder members are reinforced by extensions of metal hinges encircling said upright and secured to both sides of said wooden member. The rudders are each pivotally attached 100 along their vertical centers to the outer members of said rudder frames and each rudder of a pair is connected to the other rudder of said pair on one side of its vertical axis 105 by a cord passing across and through the hull, said cord being preferably attached back of said axis as to the forward pair of rudders and forward of said axis as to the rearward pair of rudders, and at corresponding points on the other side of the axis of each rudder in each pair steering cords 110 115 75 (see Figure 2) are attached, said cords for the stern pair of rudders extending forwardly over sheaves 76—77—78 and 120 99, and from the latter backwardly to the actuating bar 72 hereinbefore referred to and to the opposite ends of which bar said cords are secured (see Figure 20). The actuating 125 means for the forward pair of rudders 130

are arranged in a similar manner except that the steering cords pass directly from the forward part of the hull to the bar.

I combine in one device means for operating the elevating bi-planes and means for operating the rudders at each end of the hull (see Figure 11), this device comprising in each case a supporting post 93 rotatably mounted at its lower end and secured to the bottom of the pontoon in which it is located and also rotatably supported at its upper end by a bracing frame 94 embodying two legs secured at their lower ends to the bottom of the pontoon and having a bearing 5 for said post at their upper ends. A biplane operating drum 95 is rotatably mounted in a drum bearing frame 96 secured to the upper end of the post 93, a steering wheel 97 secured to the drum serving as a means for operating it. The actuating bar 72 hereinbefore referred to is secured to the lower end of the post 93, the pulleys 71, also hereinbefore referred to, being rotatably mounted on said bar, and the elevating cords 10 66, that at this point each combine the two strands secured to the elevating planes, pass about the pulleys 71 in a horizontal direction and then change direction as they pass about sheaves 98 rotatably mounted on the post 93. After passing the sheaves 98 these two strands are combined into a single strand that now includes the four actuating cords 66 hereinbefore mentioned extending from the two pairs of elevating bi-planes 15 that are in lateral alignment on opposite sides of the hull. This now single cord is secured to the drum 95 that may be rotated to wind or unwind the elevating cord and thus simultaneously operate said elevating 20 bi-planes to the same degree to cause such movement of the balloon as may be desired.

As hereinbefore stated the steering cords 25 75 are attached to the ends of the bar 72, and the operation of steering the balloon by the actuating bars will be readily understood by those skilled in the art and without further and extended explanation, it being observed that this steering operation with the feet may be aided by the hands 30 upon the wheel 97 to move the latter to turn the post 93.

By passing the cords 66 about the pulleys 35 71 on the actuating bar 72 the elevating planes may be used as ailerons in the following manner: The ends of said bars may be shaped to receive the feet of the pilot, and, assuming operation of the steering apparatus in the forward pontoon, when one end of said bar, say its right hand end, is 40 pushed forward, the forward rudder will be moved to cause the forward end of the balloon to turn to the left (see Figure 2, noting that this is a bottom view and that the terms now used refer to the balloon in its upper right position). This movement of the right

hand end of said bar forward will move the pulley 71 at that end of the bar forward and the pulley at the opposite end of said bar backward, and a pull will be exerted upon the right hand elevating plane actuating 45 cord, and the other of said cords will be slackened, and the right hand bi-plane will be depressed and the left hand bi-plane will be elevated, and this will cause the right hand side of the forward end of the balloon 50 to be raised. A similar operation of the actuating bar 72 in the pontoon at the rear will operate the rudders and elevating planes at the rear to co-act with those at the forward end of the structure as just described to turn it to the left, but the direction of inclination of the rudders will of course be reversed. That is, when the steering apparatus in either of the pontoons is 55 operated to effect a turning movement of the balloon the elevating bi-planes will be automatically operated as ailerons to aid in this turning movement, it being understood that the pilots in the two pontoons will be enabled to work in harmony by reason of 60 telephonic communication between the two pontoons.

The employment of the lifting planes as ailerons, as above described, will not interfere with their use as elevating planes, as 65 the turning of the wheels 97 will cause operation of said planes for elevating purposes irrespective of the relative positions of said planes that may have been changed by the 70 operation of the bar 72.

The vertically positioned frames 100 hereinbefore referred to and to which the extreme points 27 of the fins 26 are secured, are preferably of triangular shape and are mounted on their bases for swinging movement, one on top of each of the third or top planes 60, the upper end or point of each of these stretching frames 100 being secured to one of said points 27, and the stays 28, hereinbefore referred to, being also each secured 75 to the upper end of one of said frames. Each of said stays extends downwardly to the plane on which its frame is supported, to sheaves 101—102, and along the front spar of one of the center rigid planes 55 to a 80 sheave 103 within the passenger car (see Figure 20). After passing said sheaves 103 the two cords from stretching frames in lateral alignment on the structure are joined 85 into a single cord that may now be termed a stretching cord 104 that extends along the car, one from the front and one from the rear, to a stretching drum 105 located preferably at about the center of the length of said car and near the contracting cylinders. 90 Said stretching cords are secured to opposite sides of said drum, as within grooves in a center dividing ring 106 (see Figure 7). This drum is supported in a frame secured 95 to the under side of upper cross pieces of 100

the hull and they have worm wheels meshing with worms 107 on shafts operated as by means of handles 108. When these handles are operated to turn the drums in one direction the four triangularly shaped frames will be pulled outwardly from the gas bag, stretching the latter transversely in opposite directions on both sides, thus compressing the gas within the bag. This operation is of advantage not only to increase or decrease the size of the bag and the chamber therein but it also enables said bag to be always maintained symmetrically in the center axis of the whole structure. This apparatus also enables the bag to be always kept stiff and rigid, and when the sides of the bag are pulled outwardly the area of lifting surface is increased and the whole comprises a material element of safety.

At each end of each of the lower planes or wings 54 are attached small pontoon floats 109 (see Figure 3) made from vulcanized fabric and adapted to be inflated in any suitable manner. These pontoons are strengthened and stiffened on top as by wooden bars 110 (see Figure 23). These bars have metallic fittings 111 to which vertical struts 112, one at each end of each pontoon, is secured, the upper ends of these struts being secured to front spars of the lower wings or planes 54, said struts being suitably wire braced to said spars and to each other. On the bottom of each of said pontoons is secured another wooden bar 113 that projects beyond the end of the pontoon as a means for protecting it from injury when making a landing or when alighting on the water, and the compressed air in these pontoons provides a good shock absorber whenever the ends of the lower planes may strike an object.

Entrance to the passenger car is provided through a passageway in the bottom of the hull as by means of a ladder 84 (see Figure 5) pivotally attached to a bottom cross piece of the hull and constructed, when raised, to close said passageway.

Doors 114 closing openings in the sides of the passenger car are provided as a means of access to the motors for attention thereto.

A most important feature of my invention resides in the construction and positioning of the elevating bi-planes whereby they are exposed directly to the blast of air currents created by the propellers, said planes, when inclined downwardly, arresting backward flow of the air currents and thereby developing such currents into a lifting power. The combined dynamical lifting power of the elevating bi-planes when inclined to a proper degree and that of the rigid planes operating under speed of the structure sufficient to cause it to rise enables it to be constructed much heavier than the air, the gas bag merely serving to lessen or counteract

the effect of weight to such extent as may be desired, and this may be graduated as circumstances may require. The rate of movement of the structure may also be regulated by use of the elevating bi-planes that may be inclined to a degree to suit the speed, it being noted that the more said planes are dipped the slower may be the speed, as said planes will act as a force to elevate the structure. By graduating the amount of inclination of said lifting bi-planes at one end of the structure with reference to those at the other end ascent or descent of the structure may be regulated.

No means for inflating the bag have been shown in the drawings as it will be understood that any well known means for doing this may be provided.

It will be noted that the means for changing the size of the bag is of much value as it enables such size to be regulated to meet the conditions of the gas within the bag such size being reduced when the gas contracts and vice-versa when the gas expands.

I claim—

1. A flying structure comprising a streamline shaped inflatable bag, a long rectangular hull tightly secured to the underside of said bag, and pressing against it when the bag is inflated, sets of rigid aeroplane wings spaced apart and projecting laterally from said hull at different parts lengthwise thereof, and a motor including propelling means supported by said structure.

2. A flying structure comprising a streamline shaped inflatable bag, means controlled at the will of the operator for moving the top of the gas-bag inwardly at the forward part thereof and independently at the rearward part thereof, to depress said inwardly moved top in each of said parts of the gas-bag lengthwise thereof in a ratio corresponding to its diameters, and means secured to the underside of the bag for the support of weight thereby.

3. A flying structure comprising an elongated inflatable bag, a hull secured to the under side of said bag, sets of rigid aeroplane wings supported by and projecting laterally from said hull on opposite sides thereof and below said bag, each of said wings being spaced apart from another set of wings on the same side of the structure, each set comprising a plurality of planes located one above another, and a motor including propelling means supported by each of said sets of planes.

4. A flying structure comprising an elongated inflatable bag, a hull secured to the under side of said bag, sets of aeroplane wings rigidly supported by said hull on opposite sides at the forward part thereof, each of said sets of planes including a plurality of planes arranged one above another, similar sets of elevating planes rigidly sup-

- ported in a like manner at the after part of the structure and spaced from the forward set, and a motor including propelling means supported by each of said sets of planes.
5. A flying structure comprising a streamline-shaped inflatable bag, a long rectangularly shaped hull comprising a rigid unitary structure permanently secured tightly to the under side of said bag from the nose to the 10 rear end thereof, said hull being enlarged by downwardly projecting extensions in the median part thereof, said extensions comprising an integral part of said hull as to the entirety of the latter, and sets of rigid wings 15 attached rigidly to said hull at points adjacent to both sides of said extension.
6. A flying structure comprising an inflatable bag, a hull secured tightly to the under side of said bag, a plurality of planes 20 secured to and projecting laterally from said hull below the bag, other planes supported by the first mentioned planes and rising above the bottom of the bag on opposite sides thereof, means for connecting the last 25 mentioned planes with the bag, and propelling means supported by said structure.
7. A flying structure comprising an inflatable bag streamline-shaped, a hull passed into close contact with the under side of said 30 bag, a motor including propelling means supported by said structure, means for moving the top of the bag inwardly at the forward part thereof by force applied substantially along its center line at the top to decrease the space within the forward part of the bag, and means for independently moving 35 the rearward part of the bag inwardly by force applied substantially along the center line thereof at its top to decrease the space 40 within the rearward part of the bag and to shift the gas for lengthwise balancing of the bags.
8. A flying structure comprising an inflatable bag, a hull secured to the under side 45 of the bag, a motor including propelling means supported by said structure, a narrow contraction web extending uninterruptedly along the inside of the upper part of the bag, the edge of said web being engraved in the form of little parabola curves, and means attached to various projecting 50 points along said edge to independently move different portions of said web with the top of the bag inwardly to decrease the space 55 therein.
9. A flying structure comprising a streamline-shaped inflatable bag, a hull secured to the under side of the bag, a motor including propelling means supported by said structure, a continuous contraction web extending 60 along the top of the bag substantially at its center and depending from the inside thereof, distributors arranged in the form of parabola curves underneath said web at the forward and after parts thereof, means 65 connecting said web and said distributors, and means for independently operating the distributors to pull said web with the top of the gas bag inwardly to decrease the space within the bag at different points along 70 the bag.
10. A flying structure comprising an elongated inflatable bag, a hull secured to the under side of the bag, a motor including propelling means supported by said structure, a contraction web in the form of a strip extending continuously along the top of the bag substantially at its center, distributors arranged in the form of parabola 75 curves underneath said web, connections between said web and said distributors, and means attached to the points connecting said distributors to pull said web with the top of the bag inwardly independently at different points to decrease the space therein. 80
11. A flying structure comprising an inflatable bag, a hull secured to the under side of the bag, a motor including propelling means supported by said structure, a contraction web extending along the top of the bag substantially at its center and depending from the inside thereof, distributors arranged one at the forward part, one at the after part and one at the midsection of said bag underneath said web and in the form 85 of parabola curves, connections between said web and said distributors, and means attached to the points connecting said distributors to operate them independently each of the other for lengthwise balancing of the 90 bag. 100
12. A flying structure comprising a streamline-shaped inflatable gas bag, a hull secured to the under side of the bag, a motor including propelling means supported by said structure, a narrow continuous strip comprising a contraction web extending along the top of the bag substantially at its center and depending from the inside thereof, the edge of said web being engraved in the form of small parabola curves, each with its apex close to the bag, a distributor located underneath said web in the form of a large parabola curve, connections 105 extending from each of the points formed on said web and attached to said distributor at different spaced points thereon, and means for operating said distributor to pull the top of the bag inwardly to depress the top of said bag. 110
13. A flying structure comprising an inflatable bag, a hull secured to the under side of the bag, a motor including propelling means supported by said structure, a contraction web extending along the top of the bag substantially at its center and depending from the inside thereof, the edge of said web being engraved in the form of small parabola curves, a plurality of distributors arranged in larger parabola curves 115 120 125

underneath said web, connectors extending between the points formed between the curves on said web and said distributors, and means for independently operating 5 said distributors to pull the top of the bag inwardly to decrease the space therein.

14. A flying structure comprising an inflatable bag, a hull secured to the under side of the bag, a motor including propelling 10 means supported by said structure, a contraction web extending along the top of the bag and depending from the inside thereof, distributors extending in the form of small parabola curves one at the forward part, 15 one at the after part, and one at the mid-section of the structure, contractors attached at the points connecting said distributors at the rear part of the structure to means in said hull for operating said contractors, and contractors attached at the 20 points connecting said distributors at the forward part of the structure and extending to the contractor operating means in said hull, and means for independently operating 25 said contractor operating means to pull the top of the bag inwardly to shift the gas for lengthwise balancing purposes.

15. A flying structure comprising an inflatable bag, a hull secured to the under side 30 of the bag, a motor including propelling means supported by said structure, a narrow contraction web extending along the top of the bag and depending from the inside thereof, a plurality of distributors 35 extending in the form of large parabola curves arranged symmetrically on both sides of the crosswise center of the bag, cords extending parallel to each other at equal distances between the contraction web and 40 the said distributors, and means connected with said distributors to depress them each independently of another to shift the gas lengthwise of the bag for lengthwise balancing purposes.

45. 16. A flying structure comprising an inflatable bag, a hull secured to the under side of the bag, a motor including propelling means supported by said structure, a contraction web extending along the top of the bag and depending from the inside thereof, means connected with said contraction web to operate it to pull the top of the bag inwardly to decrease the space therein, and stretching means connected to opposite sides 50 of the bag to pull it outwardly in opposite directions and thereby depress the top of said bag.

55. 17. A flying structure comprising an inflatable bag, a hull secured to the under side of the bag, a motor including propelling means supported by said structure, a contraction web extending along the top of the bag and depending from the inside thereof, a contractor extending from said web to contractor operating means located in the hull, and 60

stretching means attached to opposite sides of the bag to pull it outwardly in opposite directions to depress the top thereof, said stretching means extending to a stretching mechanism located in the hull adjacent to 70 said contractor operating means.

18. A flying structure comprising an inflatable bag, a hull secured to the under side of the bag, a motor including propelling 75 means supported by said structure, stretching frames mounted on supports attached to opposite sides of the bag at different points along its length, stretching cords attached to said frames and extending to the hull, and stretching mechanism to which all 80 of said stretching cords are attached.

19. A flying structure comprising an inflatable bag, a hull secured to the under side of the bag, a motor including propelling 85 means supported by said structure, stretching cords attached to opposite sides of the bag at different points along its length and extending within the hull, and stretching mechanism to receive all of said stretching cords to simultaneously operate 90 them to stretch the bag at the sides and thereby depress its top.

20. A flying structure comprising an inflatable bag, a hull secured to the under side of the bag, a motor including propelling 95 means supported by said structure, stretching means secured to opposite sides of the bag and extending to said hull, and stretching mechanism connected to said stretching means whereby the sides of the 100 bag may be pulled outwardly to depress the top thereof.

21. A flying structure comprising an inflatable bag, a hull secured to the under side 105 of the bag and extending lengthwise thereof, struts secured at one end to the top of the hull and extending laterally in opposite directions diagonally upward from said hull and attached to said bag on opposite sides thereof, and means connecting the outer 110 ends of said struts and said hull.

22. A flying structure comprising an inflatable bag, a hull secured to the under side of the bag and extending lengthwise thereof, struts secured at one end to the top of 115 the hull and extending laterally in opposite directions diagonally upward from said hull and spaced at intervals along its length and attached at their outer ends to said bag, and braces connected to the outer ends of 120 said struts and extending therefrom to the bottom of said hull to which they are secured.

23. A flying structure comprising an inflatable bag, a hull secured to the under side 125 of said bag and including longérons extending lengthwise thereof at the top and on opposite sides thereof, struts pivotally attached to said longérons at intervals therealong and projecting in opposite directions

diagonally upward and attached at their outer ends to said bag, and braces extending from the outer ends of said struts downwardly to the bottom longérons of the hull 5 to which they are secured.

24. A flying structure comprising an inflatable bag, a hull secured to the under side of the bag and extending lengthwise thereof, struts extending laterally in opposite 10 site directions from said hull, a yielding tension support extending lengthwise of said bag and loosely attached thereto for lengthwise movement thereon, means for attaching said support at intervals there- 15 along to said struts, and means connecting the outer ends of said struts with said hull.

25. A flying structure comprising an inflatable bag, a hull secured to the under side of the bag and extending lengthwise thereof, 20 struts extending laterally in opposite directions from said hull, a yielding tension support extending lengthwise around the bag and loosely attached thereto for end- 25 wise movement thereon, means for connecting said support with said struts at intervals along the support, and means to connect the outer ends of the struts with said hull.

26. A flying structure comprising an inflatable bag, a hull secured to the under side 30 of the bag and extending lengthwise thereof, struts extending laterally in opposite directions from said hull, a yielding tension support extending loosely within a pocket around said bag and projecting at intervals 35 therefrom in the form of loops that are secured to the ends of said struts, and braces extending from said loops and attached to said hull.

27. A flying structure comprising an in- 40 flatable bag, a hull secured to the under side of the bag and extending lengthwise thereof, struts extending laterally in opposite directions diagonally upward from said hull, primary supports rigidly secured to the bag, 45 means for securing said primary supports at intervals to the ends of said struts, and means rigidly connecting the opposite ends of said struts to said hull.

28. A flying structure comprising an in- 50 flatable bag, a hull secured to the under side of the bag and extending lengthwise thereof, struts extending laterally in opposite directions from said hull, primary supports in the form of parabola curves rigidly secured 55 to said bag, means for connecting the points joining said curves to the ends of said struts, and means for rigidly connecting the ends of said struts with the sides of said hull.

29. A flying structure comprising an in- 60 flatable bag, a hull secured to the under side of the bag and extending lengthwise thereof, struts extending laterally in opposite directions from said hull, yielding tension

supports loosely attached to the bag for 65 movement lengthwise thereof, primary supports rigidly attached to said bag, means for connecting the primary supports and the yielding tension supports both to the ends of each of said struts, and means for connecting the ends of said struts with said hull. 70

30. A flying structure comprising an in- flatable bag, a hull secured to the under side 75 of the bag and extending lengthwise thereof, struts extending laterally in opposite directions from said hull, primary supports arranged in the form of parabola curves and rigidly attached to the bag, a yielding tension support loosely attached to the bag 80 and having loops engaging points at the intersection of the curves of the primary supports, said loops each being connected to the end of one of said struts, and means for connecting said struts to said hull. 85

31. A flying structure comprising an in- flatable bag, a hull secured to the under side 90 of the bag and extending lengthwise thereof, members of a rigid bi-plane secured to and extending from the upper and lower 95 longérons of said hull on opposite sides thereof, rigid planes supported on and above said bi-planes on opposite sides of the hull, and a motor including propelling means supported by said structure. 95

32. A flying structure including an elongated hull, two sets of rigid bi-planes secured to said hull one in front and the other in the rear of the center of gravity of said hull and projecting in opposite directions 100 therefrom, elevating bi-planes pivotally attached to the rear spars of each pair of rigid bi-planes and projecting behind the rear edges of said rigid planes, said pivoted elevating bi-planes being of substantially the 105 same size and arranged symmetrically on both sides of said structure, and a motor including propelling means supported on opposite sides of said hull by each of said rigid bi-planes in position for the current of air 110 created by said motor to be forced against said pivoted bi-planes.

33. A flying structure comprising a stream-line-shaped inflatable bag, a hull secured to the under side of said bag and extending 115 lengthwise thereof, bi-planes rigidly secured to said hull at spaced locations thereon and projecting laterally therefrom in opposite directions, elevating bi-planes pivotally attached to the rear spars of each pair of rigid bi-planes and projecting substantially 120 behind the rear edges of said rigid bi-planes, said pivoted elevating bi-planes being substantially equal in size and symmetrically arranged lengthwise in the front and rear 125 of the crosswise central line of gravity, and a motor including propelling means supported on opposite sides of said hull by each

of said rigid bi-planes in position for the current of the air created by said motor to be forced against said pivoted bi-planes.

34. A flying structure comprising an elongated inflatable bag, a hull secured to the under side of said bag and extending lengthwise thereof, two sets of rigid bi-planes secured to said hull, one in front and the other in the rear and projecting laterally in opposite directions therefrom, elevating bi-planes pivotally attached to the rear spars of each pair of rigid bi-planes and projecting substantially behind the rear edges of said rigid bi-planes, said pivoted elevating bi-planes being all substantially equal in size and symmetrically arranged lengthwise and on both sides of the center of gravity of said flying structure, and a motor including propelling means supported on opposite sides 15 of said hull by each of said rigid bi-planes in position for the current of air created by said motor to be forced against said pivoted bi-planes.

35. A flying structure comprising an inflatable bag, a hull secured to the under side of said bag, a rectangularly shaped frame extending laterally from the hull on opposite sides thereof at a distance from its end, each of said frames including a single upper 20 and a single lower member, said members being connected by an upright at their outer ends, rudders pivotally mounted intermediate their ends on said uprights, and means for operating the rudders.

36. A flying structure comprising a streamline-shaped inflatable bag, a long rectangularly shaped hull secured to the under side of said bag, a U-shaped frame attached at both its free ends to said hull, wire bracing extending between members of said frame in a vertical plane, the outer upright member of said frame being wire braced to the hull in a horizontal plane, a rudder pivotally mounted on said upright member, and means for operating said rudder.

37. A flying structure comprising an inflatable bag, a hull secured to the under side of said bag, a set of planes rigidly secured to said hull and projecting laterally therefrom in opposite directions, another set of planes rigidly secured to said hull in spaced relation to the first set and projecting from the hull in opposite directions, a pair of rudders supported by said hull on opposite sides thereof forward of one set of planes, another pair of rudders supported by said hull on opposite sides thereof back of the other set of planes, and means for operating said rudders.

38. A flying structure comprising a streamline-shaped inflatable bag, a long rectangularly shaped hull secured to the under side of said bag and extending from the nose to the rear end thereof, a set of rigid wings projecting laterally from said hull at the point of transverse center of gravity of the front half of the flying structure, another set of rigid wings projecting laterally from said hull at the point of transverse center of gravity of the rear half of said flying structure, a motor supported by each of said sets of rigid wings, a projection in the form of a small cabin extending downwardly below each set of rigid wings and below said motors, a single wheel mounted in the bottom of each projection and projecting partially above said bottom, and means for concentrating weight of the motors on said wheel to prevent the transference of shock on said wheel to said motors through the medium of the wings.

39. A flying structure comprising an inflatable bag, a hull secured to the under side of the bag, contracting means attached to the inside of the bag at its top and projecting downwardly through a hole in the bottom of said bag, a plate located outside of the bag and surrounding said hole, a plate located inside of the bag and secured to the first mentioned plate to clamp the bag between said plates, and a stuffing box structure rising from the plate within the bag and including a spirally formed member arranged to permit passage of said contracting means without escape of gas from within the bag.

40. A flying structure comprising an inflatable bag, means secured to the under side of the bag for support of weight thereby, a contraction web extending from the inside of the bag and having its edge engrailed in the form of small parabola curves, and means attached at the points joining said curves to operate said web to pull different positions thereof independently inwardly to shift the gas for lengthwise balancing.

41. A flying structure comprising an inflatable bag, means secured to the under side of the bag for the support of weight thereby, a contraction web extending from the inside of the bag, distributors arranged in parabola curves opposite said web, means connected to the distributors and web, and contractors for independently operating said distributors to pull the bag inwardly to shift the gas for lengthwise balancing purposes.

42. A flying structure comprising an inflatable bag, means secured to the under side of the bag for the support of weight thereby, a contraction web extending from the inside of the bag and with its edge engrailed in the form of small parabola curves, distributors formed in larger parabola curves located opposite said web, means connecting the points between the curves of the web and said distributors, and

means attached to the points between said distributors for pulling the bag inwardly.

43. A flying structure comprising a stream-line shaped inflatable gas-bag, means controlled at the will of the operator for moving the upper part of the bag inwardly from opposite sides thereof to decrease space

therein in proportion to each of the various diameters along the whole length of the bag, and means secured to the under side of the bag for supporting weight thereby. ¹⁰

JOHN TWARDUS.
